UNITED STATES PATENT OFFICE.

LEWIS J. BRABANT, OF MILWAUKEE, WISCONSIN.

CALENDAR.

Application filed July 10, 1919. Serial No. 309,860.

To all whom it may concern:

Be it known that I, LEWIS J. BRABANT, a citizen of the United States, of Milwaukee, in the county of Milwaukee and State of Wisconsin, have invented a new and useful Improvement in Calendars, which invention is fully set forth and illustrated in the following specifications and accompanying drawings.

10 The object of this invention is the making of a simple mechanical device comprising three to five simple flat parts of cheap material adapted to slide upon one another into indicated positions in which there will be 15 produced to the vision a calendar in the usual and accepted form, with proper number of days and co-incidence of dates with days of the week, of any month in any year, as desired; and to make such device useful 20 besides for reference purposes to an extended span of years, also as a current calendar for ten or twelve years.

A further object of the invention is to provide an easily operated and easily understood device, so arranged that when any selected month designation is brought into observing position in connection with a table of lunar month day designations, the correct table of excess month day designations 30 for the selected month will be properly positioned with respect to the table of lunar month day designations.

In the drawings,

Figure 1 is a plan view of the improved 35 calendar with parts broken away,

Figure 2 is a similar view with the front or mount removed,

Figure 3 is a plan view of the plate carrying the year and week day designations,

40 Figure 4 is a side view of the same,

Figure 5 is a plan view of the part carrying the table of lunar month day designations,

Figure 6 is an end view of the same,

45 Figure 7 is a plan view of the part carrying the month designations and the excess day tables,

Figure 8 is a partial plan elevation showing an alternate arrangement,

50 Figure 9 is a plan view of the covering slide.

The improved calendar consists of three principal parts, which are preferably of celluloid, but may be of any other suitable material, and the three parts are mounted to slide upon each other. These parts are in

the form of plates, indicated at A, B and C respectively. The plate A is mounted to slide vertically on the plate B, and the plate B is mounted to slide laterally on the plate C, the plates A and B being mounted in any suitable form of guide, as for instance the character of guide shown at 14 and 15 in Figures 4 and 6, the said guides being formed by overlined flanges on the edges of 60 the plates B and C, and any suitable means may be provided for facilitating the moving. The plate A is provided on its forward face with a plurality of vertical lines, dividing the said face into columns, and in 65 these columns at the upper part of the plate there is arranged a number of month indications, as shown at 1. At the lower part of the plate a plurality of tables 2 of excess days over a lunar month are arranged, 70 in such manner that when any month in the upper table is in observing position, the proper table of excess days will be in correct position with respect to the tables of 75 the lunar month day designations. The 80 plate B, Figure 5, has tables 3 of the month day designations, and has apertures 4 through which the tables of excess days on the plate A may be observed. The plate B also carries an aperture 5 through which 85 month designations on the plate A may be observed.

The plate C, which is the mount or front of the calendar has an aperture 6, of sufficient size to expose a table of month days. 90 Above this aperture there is a table 7 of week day designations, and an aperture 8 above said table, through which the month designations 1 may be observed. Above such aperture 8, the plate C has a plurality 95 of vertical columns, which contain year designations 9.

A slide 10 is mounted to move transversely of the plate C, on the back thereof between guides 11, and this slide has a notch 100 12 in its upper edge. The slide is of such width as to hide the aperture 8, and the adjacent year designations of the table 9, and the notch 12 is of a width corresponding to the width of the columns in which 105 the year designations are arranged. It will be evident that by moving the slide laterally, as indicated by the arrows in Figure 2, any desired year designation in the table 9 may be exposed. Instead of a notch, the 110 slide 10 may have a transparent portion of a size corresponding to the notch. The

slide 10 is so arranged that the upper edge thereof is at the upper edge of the table 7 of week day designations. In order to extend the operation of the calendar, that 5 is to make it a perpetual calendar, additional year designations may be arranged upon a plate 13 which may be secured to the face of the plate C over those year designations of the table 9 which are above the 10 upper edge of the slide 10. When the plate 13 is so arranged, with the year designations on the rear face, as indicated in Figure 1, only one year designation will be exposed. This plate 13 may be secured to the 15 plate C in any usual or desired manner, as for instance by hinging it to the plate C to be folded down over the year designations on the said plate. Referring to Figure 3 it will be seen that there are year 20 designations 9 below the aperture 8. These year designations are shown by reversing the slide 10, so that the notch 12 is at the lower edge of the slide.

Referring to Figure 8, it will be seen that 25 instead of the plate 13 I may use a plate 16, whose ends overlie the ends of the slide 10, and are secured to the guides 11. This plate is notched deeply on its under face at the aperture 6 of the plate C, so that 30 the notch 12 of the slide 10 is fully exposed when the said notch is in the notch of the plate 16. The plate also has a central extension overlying and concealing the year 35 designations of the table 9 above the upper edge of the slide 10.

The table of day designations on plate B is arranged in 13 columns and 6 rows. Numerals are worked in the columns as follows, beginning in the top row, seventh 40 square, the figure 1, followed consecutively by 2, 3, 4, 5, 6 and 7; in the square below 1, the figure 8, the squares to its left being numbered consecutively downward to 2 and the squares to its right consecutively upward to 14; each additional row being provided with numerals reading consecutively upward from left to right, and bearing relation to the figures in that above it in that each figure is seven more than that 45 in the square immediately above it, the figures in any row ending with 28 and the remaining squares left blank. Apertures 4 are provided by cutting out the squares immediately below those containing figures 50 22, 23 and 24 wherever they occur, through 55 which numerals following consecutively from 28 upward are revealed.

It is apparent that any seven adjacent columns in the combined date group may 60 be read consecutively and from row to row downward from 1 to 28, 29, 30, or 31 respectively, according to the adjustments of the rear slide A, and by concealing all parts of the group except seven vertical adjacent 65 columns and disclosing only seven, as for

instance through a rectangular aperture as provided in part C (Fig. 3), such consecutive group of figures is disclosed to the vision.

Part B is adapted to fasten in rear of 70 part C (Fig. 3) by grooves, rivets, or in any other practicable manner so that it may be slid or otherwise moved horizontally into any of the seven possible positions by which its columns will correspond and register with the seven columns of C and the date numeral "1" will register with any of the days of the week marked in such seven columns, when also one of the designations of months on A showing through apertures 75 5 80 (Fig. 5) and 8 (Fig. 3) may be brought to register in column with the designation of any year numeral marked in such seven columns.

The apertures 6 and 8 of the plate C are 85 rectangular, and equal in width to 7 columns and laterally bounded by the same vertical lines. The upper aperture, 8, is of such height and so positioned that when the calendar is assembled it coincides with 90 the aperture 5 in part B, (Fig. 3) and in seven possible positions of B reveals to the vision seven adjacent columns of the month group of part A (Fig. 1). The lower aperture, 6, is of height equal to the six rows 95 of the main date group of part B, and is so positioned that when the calendar is assembled its horizontal lines coincide with the horizontal lines of such date group and there is revealed to the vision through it 100 seven complete columns, of the date group, with figures reading consecutively in the usual form of monthly calendar.

Having described my invention, I claim:

1. In a calendar, a slide having apertures, 105 a second slide movable vertically thereon and having thereon a month group with the months classified in rows according to the number of days in them, each row of months having corresponding thereto a specially arranged and positioned row of figures, the distance between and relative position of corresponding rows being similar in each case so that they may show coincidentally through the apertures in the first named 110 slide, said first named slide having thereon a date group of sufficient numerals to form a twenty-eight day month so that when a row of months show through one aperture, there will appear at further apertures following the figures 28 appropriate numerals extending the date group to 29, 30 or 31, as appropriate to the months shown, substantially as described.

2. In a calendar, a laterally moving slide 125 having apertures and marked with a date group and bearing at its rear a vertically movable slide marked with rows of the names of months classified in rows according to the number of days in them, one row of 130

- such months appearing at a time through an aperture with corresponding rows of figures appropriate to the months shown appearing through other apertures, and a 5 selected column of the year and week day designations, and a third plate having a table of month designations and tables of designations of days in excess of a lunar month, 50 said plate being movable vertically with respect to the second named plate and the tables of the said last named plate being so arranged that when a selected month is 55 brought into a position in alignment with a selected column of year and week day designations and between such designations, the correct table of excess days for the month will be in proper position in the table of 60 month day designations.
5. In a calendar of the class described, a plurality of plates having guided sliding movement on each other, sundry of the plates having openings through which data 65 on other of the plates is visible, said plates carrying tables of designations of years, months, week days, lunar month days and excess days so arranged on the plates that when by sliding the plates upon each other 70 a selected month designation is brought into a prescribed position with respect to a selected year designation, and a selected table of lunar day month designations is brought into proper position with respect to the week 75 day designations, the designations of the days for the month in excess of the days of the lunar month will also be in proper position with respect to the table of lunar month day designations. 80
6. In a calendar of the class described, a plate having tables of lunar month day designations, a second plate having guided movement of the first plate, and provided with tables of month and of month day designations in excess of a lunar month, and so arranged upon the plate that when a selected month designation is brought into observing position above the tables of the first plate, the correct table of excess month 85 day designations will be properly positioned with respect to the table of lunar month day designations. 90
- LEWIS J. BRABANT.
